GARDEN ROW MARKER

Larry L. Shroyer, 306 Railroad St.,
Union City, Mich. 49094

Filed Aug. 1, 1974, Ser. No. 493,538

Term of patent 14 years

Int. Cl. D31—00

U.S. Cl. D35—1

FIG. 1

FIG. 2

FIG. 3

FIG. 4

FIG. 5

FIG. 6

FIG. 7

FIG. 1 is a side elevational view of a garden row marker showing my new design;
FIG. 2 is a side elevational view as taken from the right of FIG. 1;
FIG. 3 is a side elevational view as taken from the left of FIG. 1;
FIG. 4 is a top plan view of my new design;
FIG. 5 is a bottom plan view of the design;
FIG. 6 is a sectional view as taken through section VI-VI of FIG. 1; and
FIG. 7 is a sectional view as taken along section VII-VII of FIG. 1.

I claim:

The ornamental design for a garden row marker, substantially as shown.
